United States Patent Office

Des. 212,980
Patented Dec. 17, 1968

212,980

ADDRESS LABEL DISPENSER

John W. Desmond, 104 Walter Drive, R.D.,
Media, Pa. 19063

Filed July 25, 1967, Ser. No. 7,971

Term of patent 14 years

(Cl. D74—1)

Fig. 1

Fig. 2

Fig. 3

Fig. 4

FIG. 1 is a perspective view of the address label dispenser showing my new design;

FIG. 2 is a rear end elevational view of the address label dispenser shown in FIG. 1;

FIG. 3 is a side elevational view thereof, the side opposite thereto being similar in appearance; and

FIG. 4 is a bottom plan view thereof.

I claim:

The ornamental design for an address label dispenser, substantially as shown and described.
